ANIMATED FIGURE TOY

Joseph L. Bonanno, Madison, N. J., assignor to
The Lionel Corporation, New York, N. Y., a
corporation of New York

Application August 1, 1951, Serial No. 239,681

3 Claims. (Cl. 46—12)

1

The present invention relates to animated figure toys and is more particularly directed to toys having a toy house with figure which comes out of a normally closed door and returns to the toy house after which the door closes.

The present invention relates to improvements in toys for these purposes over those previously shown in patents to Handy No. 1,966,031, dated July 10, 1934, and Bonanno No. 2,138,367, dated November 29, 1938.

The present invention relates more particularly to the electromagnetically operated mechanisms for shifting the figure and opening the door. Here the parts shown are developed for low cost manufacture, ease of assembly and repairs and without sacrifice of utility or play value.

The toy building, apart from the door and figure operating mechanism is shown and claimed in my concurrently filed application, Toy Buildings, Ser. No. 239,682.

The accompanying drawings show, for purposes of illustrating the present invention, one embodiment in which the invention may take form, it being understood that the drawings are illustrative of the invention rather than limiting the same.

In the accompanying drawings:

Figure 1 is a perspective view of the animated figure toy with the door open;

Figure 2 is a horizontal section on the line 2—2 of Figure 5 with the door closed;

Figure 3 is an inverted plan view with parts broken away and the bottom cover removed;

Figure 4 is a vertical section on line 4—4 of Figure 3;

Figure 5 is a section on the line 5—5 of Figure 3 with parts in elevation; and

Figure 6 is a section on the line 6—6 of Figure 3.

As shown in the perspective view of Fig. 1, the animated figure toy has a base 10, a house 11 with the door 12 open in the doorway or door opening, and a toy figure or manikin simulating the gateman or signal man. The device simulates the gateman's shanty alongside the usual railroad track.

As shown in the drawings, the base 10 is, for convenience, a rectangular shaped sheet metal member with downwardly extending flanges 15. It supports the toy house 11. The door 12 for the toy house has an upwardly extending pintle 16 entering into the recess in the top of the doorway of the toy house and has a pivot post 17 which passes down through an opening in the base 10. The lower end of the pintle 16 carries a molded plastic gear member 18 with a lower

2

flange 19 preferably somewhat larger in diameter than the outer diameter of the gear teeth.

The base 10 carries a pivot post 20 some distance beyond the other edge of the doorway. This pivot post carries a sector shaped arm 21 having teeth 22 which mesh with the teeth of the gear 18. The lever arm 21 is held in place on pin 20 by a spring washer 23 and is provided with pairs of upwardly extending prongs 24, 25 which reach nearly to the lower surface of the base 10 so as to keep the arm from shifting out of position. It is held against separation from the gear 18 by the flange 19. The sector arm 21 carries a post 26 which extends up through an arcuate slot 27 in the base and carries a manikin or figure 13 above referred to.

The arm 21 is biased to the position shown in full lines in Fig. 3 by a spring 28. When the parts are in this position the figure or manikin is inside 20 the toy house and the door of the toy house is closed.

The base 10 also carries a solenoid coil 30 having a magnetizable plunger 31 whose free end 32 bears against the edge 33 of the lever arm 21. 25 One lead 34 from the coil is connected to a vertical rod 35 insulated from the base 10 and the other end of the coil is grounded to the base 10. Rod 35 and a similar uninsulated rod 36 are employed as shown in the application above referred to and hold the house unit on the base and provide current connections under the roof of the toy house. The mechanism carried in the base 10 is covered and protected by a bottom cover member 37, Figs. 4 and 5.

35 Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. A toy comprising a toy house having a doorway, a base supporting the toy house, a door pivotally supported by the base and the top of the doorway near one edge thereof for swinging outwardly, a gear carried by the lower door pivot below the base, a toothed sector of larger radius than the radius of the gear, meshing with the gear and pivoted to the base beyond the other edge of the doorway, a spring acting on the sector to hold the door closed, a post extending upwardly from the sector and passing through a slot in the base partly behind the doorway and partly in front of it, a figure carried on the post

and movable through the doorway when the sector moves the door open and retreating into the building when the door closes, and a solenoid coil having a horizontal axis at substantially the level of the sector and an armature plunger in the coil acting on the edge of the sector to move it against the spring to open the door and advance the figure.

2. An electrically operated figure toy comprising a base, a horizontal solenoid coil carried by the base and carrying a magnetizable plunger below the base, a flat sheet metal arm pivotally carried by the base and having gear teeth at its outer edge, the arm having a side edge engageable with the plunger and being shiftable by the plunger when the coil is energized, a spring holding the arm in position to be moved by the plunger, a figure carried by the arm above the base, the figure having a support which passes through a slot in the base, a gear supported from the base and meshing with the gear teeth on the arm, a toy house above the base provided with a doorway across the slot in the base, and a door pivotally carried in the doorway and drivingly connected to the gear to be actuated to closed po-

sition by the spring and to open position by the plunger.

3. A toy comprising a toy house having a doorway, a base supporting the toy house, a door pivotally supported by the base and the top of the doorway near one edge thereof for swinging outwardly, a gear carried by the lower door pivot below the base and having a lower flange extending beyond the teeth, a toothed sector meshing with the gear, a pivot post carried by the base and supporting the toothed sector, the sector having upwardly extending members adapted to engage the lower surface of the base and limit upward movement of the sector, the flange keeping it in engagement with the gear teeth, a spring biasing the sector to position the door in one position, and an electromagnet having a plunger engaging the sector to shift the door to the other position.
